UNITED STATES PATENT OFFICE.

JOHN T. MERRILL, OF MOUNT AYR, IOWA, ASSIGNOR OF TWO-THIRDS TO
GEORGE S. ALLYN AND JOHN O. FRY, BOTH OF SAME PLACE.

BALANCED VALVE.

SPECIFICATION forming part of Letters Patent No. 356,148, dated January 18, 1887.

Application filed October 6, 1886. Serial No. 215,488. (No model.)

To all whom it may concern:

Be it known that I, JOHN T. MERRILL, a citizen of the United States, residing at Mount Ayr, in the county of Ringgold and State of Iowa, have invented a new and useful Improvement 5 in Balanced Valves for Locomotives and other Steam-Engines, of which the following is a specification.

My invention relates to improvements in 10 balanced valves; and it consists of the peculiar combination of devices and novel construction and arrangement of the various parts for service, substantially as hereinafter fully described, and particularly pointed out in the 15 claims.

The primary object of my present invention is to provide improved means which can be 20 readily and easily adapted to the ordinary construction of locomotive valves of the long slide-valve class.

A further object of my invention is to provide a balanced valve upon which the steam in 25 the chest of the locomotive or other engine is capable of exerting an upward or counter current in such a manner that the valve shall be evenly and accurately balanced, so that it can be moved or reciprocated with great ease.

A further object of my invention is to improve the valve in minor details, so that it 30 shall possess superior advantages over others which have preceded it in points of simplicity, strength, and durability of construction, effectiveness of operation, and cheapness of manufacture.

In the accompanying drawings, which illustrate 35 a balanced slide-valve embodying my improvements, Figure 1 is a side elevation of the same in position in a steam-chest of the engine or locomotive. Fig. 2 is a top plan view. Fig. 3 is a vertical longitudinal sectional view 40 on the line $\alpha\alpha$ of Fig. 2, and Fig. 4 is a vertical transverse sectional view on the line yy of the same figure. Fig. 5 is a detached detail view of one of the disks or plates. Fig. 6 45 is a like view, partly broken away and in section, of the expansible ring.

Referring to the drawings, in which like letters of reference denote corresponding parts in all the figures, A designates the ordinary 50 slide-valve that is extensively used in locomo-

tive-engines and which is oblong in form. The valve is provided with a flange or ledge, a , at its lower edge, and the back a' thereof is raised or extended upwardly slightly for the purpose of receiving my improved appliances for counteracting the downward pressure of the steam upon the valve. A yoke, B, of the ordinary common pattern, is fitted around the back of the valve, and this yoke rests upon the ledge or flange a of the valve, as is usual. 55

C designates a disk, which is rigidly affixed to the upper side of the back a' of the slide-valve A, and the edges of this disk or plate are extended beyond the side edges of the valve, as shown, so that a portion of the lower side of the disk is exposed to adapt the steam in the chest to press upwardly upon the disk, this counter-pressure of the steam serving to evenly and perfectly balance the valve, so that it can be moved with the greatest ease in the 60 chest. The disk is provided on its underside with depending flanges c , which bear or impinge against the upper sides of the valve, and thus prevent lateral displacement of the disk on the valve, and the disk is more securely 65 connected to the valve by means of screws c' , which pass through suitable openings in the disk and are screwed into suitable threaded sockets in the back a' of the valve.

The upper surface of the disk or plate C is 70 provided with channels or grooves d , which are arranged at right angles to each other. These grooves intersect or cross one another at the center of the disk, and they are arranged in such a position on the disk or plate 75 that their outer terminal ends are equidistant at the side edges of the back a' of the valve, as clearly shown.

E designates a series of springs, which are preferably flat, as shown. These springs are 80 arranged in the radial grooves or channels of the disk or plate C, which, for the sake of convenience, I will hereinafter term the "pressure-plate." The inner ends of the springs are arranged near the point of intersection of the 85 radial grooves or channels, but the said ends of the springs are out of contact with each other. The springs are rigidly secured or affixed at their inner terminal ends to the fixed pressure-plate C by means of vertical screws, 90 95 100

thus independently securing the said springs in place, and the outer or free ends of the springs extend or project beyond the periphery of the fixed pressure disk or plate C, the 5 said outer ends of the springs being slightly curved or bent, as at e, for a purpose to be hereinafter described.

At the point of intersection of the radial grooves of the fixed pressure disk or plate C is located a vertical post or stud, F, which is rigidly fixed in the center of the pressure-disk and the back of the slide-valve A. This central post is extended above the pressure-disk and is exteriorly screw-threaded, and the upper end of the post passes through a central aperture, g, formed in the re-enforcing plate G, which is fitted upon the pressure-disk. This re-enforcing plate or disk is of substantially the same shape and size of the pressure-plate, and it is rigidly connected or held upon the pressure-disk by means of a burr or nut, g', which is screwed upon the upper extremity of the threaded post and impinges upon the re-enforcing plate or disk.

25 The radial grooves or channels in the pressure-plate are gradually deepened toward the periphery of the disk, and the inner ends of the springs are thereby elevated above the outer terminal ends of the same. The springs are first tempered and adjusted before being applied to the pressure-disk, and they are free to move or play vertically in the outer deeper portions of the grooves or channels. The re-enforcing plate is pressed firmly down upon the pressure-disk by the nut or burr impinging upon the upper side thereof, and this said plate bears upon the inner ends of the springs at the points where they are connected to the pressure-disk, so that the said inner ends of 40 the springs are more securely and firmly held upon the pressure-disk, while the necessary movement or play is permitted to the outer free ends of the same, as will be very readily understood.

45 The re-enforcing plate is provided on its upper side with an integral boss or stud, g², which has a central cavity or depression, g³, in which is located or arranged the burr or nut g', that forces the said plate upon the pressure-plate, the said nut being wholly concealed within the cavity of the boss.

A ring or annulus, H, is fitted around the periphery of the re-enforcing plate and rests upon the outer bent or curved ends of the 55 springs, by which the said ring is normally pressed or forced upwardly. This ring or annulus is divided, and in one of the ends thereof is fitted an inclined plate or link, h, which is rigidly secured in place by means of a transverse pin or other suitable means. The free end of the plate or link is extended beyond the end of the ring to which it is connected, and works or plays in an inclined slot, h', that is formed in the other end of the ring 60 or annulus. By means of this connecting-link being rigidly secured to one end of the ring or annulus and working in a slot in the opposite

end, the ring or annulus is free to expand and contract under varying degrees of temperature of the valve, and the ends thereof are connected and kept in line with each other.

I designate a friction-plate, which is provided with a central opening, i, through which passes the central boss or stud of the re-enforcing plate. This friction-plate rests upon the expansion-ring, and is elevated by the latter into contact with the inner side of the cover or roof of the steam-chest of the engine. The friction-plate also rests upon the re-enforcing plate, and is connected thereto by a dowel-pin, 80 j, so as to prevent displacement of the friction-plate from the valve during the strokes thereof.

By means of the hereinbefore-described construction I provide a valve which presents a surface upon which an upward pressure is exerted by the steam of the chest, which counteracts the enormous downward pressure of the steam, and thereby perfectly balances the valve so that it can be reciprocated or moved very easily and freely.

90 The invention is especially designed to be applied to locomotive-valves of the oblong class, for which purpose I have found it very efficient; but it can be applied to any common form of slide-valve to balance the same.

95 The improvements are very simple and strong in construction and efficient and reliable in operation. They can be applied at a very small cost to the common form of valve, and render the same very much more efficient in 100 operation.

I attach especial importance to the fixed pressure-plate carrying the springs, the expansion-ring supported on the springs, and the friction-plate resting upon the rings, and forced 105 thereby into contact with the roof or cover of the steam-chest, as therein lies the gist of my invention.

Having thus fully described my invention, what I claim as new, and desire to secure by 110 Letters Patent, is—

1. The combination, with the slide-valve, of the pressure-plate affixed thereto, the springs extending at their free ends beyond the plate or disk, the annulus or ring supported on the 115 free ends of the springs, and the friction-plate resting on the annulus or ring and pressed thereby into contact with the cover of the steam-chest, substantially as described, for the purpose set forth.

2. The combination, with the slide-valve, of the fixed pressure disk or plate, the re-enforcing plate secured upon the pressure-disk, the springs intermediate of the pressure and re-enforcing disks or plates and having their 125 free ends extended beyond the peripheries of the same, the expansion ring or annulus fitted around the re-enforcing plate and resting upon the free ends of the springs, and the friction-plate, substantially as described, for the purpose set forth.

3. The combination, with the slide-valve, of the pressure plate or disk rigidly affixed thereto and having its edges or periphery extended

beyond the sides of the valve to provide a surface against which an upward pressure of steam can be exerted, the springs fixed to the pressure-plate and having their free ends arranged 5 equidistant around the edges of the said plate, the re-enforcing plate rigidly secured to the pressure-plate, the expansion-ring fitted around the re-enforcing plate and resting upon the free ends of the springs, and the friction- 10 plate, substantially as described, for the purpose set forth.

4. The combination, with the slide-valve, of the pressure plate or disk rigidly affixed thereto and having the radial channels or grooves 15 in its upper side, the re-enforcing plate rigidly affixed to the pressure-plate, the springs located in the radial channels of the pressure-plate and secured at their inner ends thereto, the expansion-ring surrounding the re-enforcing 20 plate and resting upon the free ends of the springs, and the friction-plate carried by the expansion-ring, substantially as described, for the purpose set forth.

5. The combination, with the slide-valve, of the pressure-plate rigidly affixed to the valve, the central-threaded stud affixed to the pressure-plate, the re-enforcing plate bearing upon 25 the pressure-plate and having a central boss

provided with a transverse opening through which the threaded stud passes and a cavity 30 in its upper side, the nut fitted on the threaded stud and located in the cavity of the re-enforcing plate, the expansion-ring fitted around the re-enforcing plate, and the friction-plate carried by the expansion-ring, substantially as 35 described, for the purpose set forth.

6. The combination, with the slide-valve, of the fixed pressure-plate thereon, the re-enforcing plate, the radial springs intermediate of the pressure and re-enforcing plates, the expansion-ring fitted around the re-enforcing plate and resting upon the free ends of the springs, the said ring being divided and having an inclined link affixed in one end and an inclined slot in which the free end of the link 40 works, and the friction-plate carried by the expansion ring, substantially as described, for the purpose set forth.

In testimony that I claim the foregoing as my own I have hereto affixed my signature in 45 presence of two witnesses.

JOHN T. MERRILL.
